(57) **CLAIM**

The ornamental design for a laminate panel with translucent wood design, as shown and described in the Figures.

DESCRIPTION

FIG. 1 is a facing, perspective view of a laminate panel portion incorporating the translucent wood design as used in a partition structure;

FIG. 2 is a close-up perspective view thereof;

FIG. 3 is a front elevational view thereof;

FIG. 4 is a cross-sectional view of FIG. 3, taken along line 4—4 in FIG. 3;

FIG. 5 is a cross-sectional view of FIG. 3, taken along line 5—5 in FIG. 3;

FIG. 6 is a cross-sectional view of FIG. 3, taken along line 6—6 in FIG. 3;

FIG. 7 is a cross-sectional view of FIG. 3, taken along line 7—7 in FIG. 3; and,

FIG. 8 is an enlarged cross-sectional view shown along line 8—8 in FIG. 7.

The rear of the laminate panel with translucent wood design is unornamented.

The broken lines showing environment in the drawings are included for illustrative purposes only and form no part of the claimed design. The outer broken line boundaries in Figures depicting the boundaries of the claimed design indicate that a specific length, width, and shape form no part of the claimed design and are for illustrative purposes only.
